UNITED STATES PATENT OFFICE.

ORVILLE L. PARMENTER, OF MILWAUKEE, WISCONSIN.

CIGAR-CELL SERIES.

SPECIFICATION forming part of Letters Patent No. 598,483, dated February 1, 1898.

Application filed December 10, 1894. Serial No. 531,368. (No model.)

To all whom it may concern:

Be it known that I, ORVILLE L. PARMENTER, a citizen of the United States, residing at Milwaukee, in the county of Milwaukee and State 5 of Wisconsin, have invented new and useful Improvements in Cigar-Cell Series, of which the following is a specification.

This invention relates to certain improvements in paper cigar pockets or cells.

10 The object of the invention is to provide a series of detachable paper cigar pockets or cells of an improved construction, so that all the pockets of the series can be filled with cigars of the same or different sizes or shapes, 15 and one or more of the pockets can be easily and quickly detached with their contained cigars without injury to the pockets detached or to those remaining in the series, and so that each pocket detached will be intact and 20 in perfect condition to hold and protect its contained cigar in the pocket or elsewhere.

The invention consists in certain novel features of construction and in arrangements and combinations of parts more fully and 25 particularly described and pointed out hereinafter.

Referring to the accompanying drawings, Figure 1 is a rear elevation of a series of the connected cigar-pockets. Fig. 2 is a front 30 elevation thereof. Fig. 3 is an edge view of a pocket. Fig. 4 is a top plan of a series of the connected pockets, several of the pockets containing cigars and the remaining pockets shown folded or collapsed. Fig. 5 is a detail 35 perspective view of one of the pockets detached and containing a cigar. Fig. 6 is a detail view of the paper blank from which a single pocket is folded.

The series of pockets is composed of a single 40 backing-sheet of suitable paper having parallel transverse equally-spaced lines of perforations formed therein, with a series of parallel closely-arranged independently-formed paper cigar-pockets cemented on one side of 45 the sheet, with the lines of perforations through the sheet between the pockets and separating them.

In the drawings, *a* is the single elongated 50 rectangular paper strip, sheet, or backing of the same length as the series of pockets to be formed, but of slightly greater width than the length of a pocket. This sheet has the

transverse lines *a'* of perforations usually formed therein before the pockets are applied to the sheet. These lines of perforations are 55 formed parallel with each other and equally spaced and preferably extend completely across the backing-sheet.

Each pocket *b* is formed of a single rectangular sheet of flexible paper folded by suitable means to form the closed front of the pocket, the two collapsible sides, and the rear wall, where the two ends of the paper are brought together or overlapped at *b'* and pasted or cemented throughout their lengths 65 to the backing-sheet in the space between two adjacent lines of perforations therein.

The two sides of each pocket are rendered collapsible by each having a single inward angular bend or fold *b*² throughout its length, 70 so that the pocket can be entirely collapsed and can be easily distended to its full capacity by the insertion of a cigar at the upper open end of the pocket. Each pocket is thus formed of its own separate sheet of paper and 75 is entirely independent of and formed separately from the remaining pockets of the series, the pockets of the series being connected only by the single thickness of the backing-sheet. 80

The pockets are arranged parallel to each other and closely together, with their edges touching or almost touching when the pockets are collapsed, so that they are separated only by the lines of perforations through the 85 single thickness of backing-sheet between them and so that each pocket occupies the full space between the lines of perforations at each edge thereof. After all the pockets of a series have been pasted or cemented on 90 the single backing-sheet the short lower longitudinal edge *a*² of the backing-sheet is folded over the lower ends of the pockets, which are pressed tightly closed, and is pasted or cemented to the outer faces thereof to permanently close the lower ends of the pockets. 95

By reason of the single backing-sheet and the fact that the perforations extend through this sheet only and can be formed therein before the pockets are applied thereto, and as each pocket is formed independently of its own sheet or paper, the series of cigar-pockets described can be most rapidly and economically manufactured by machinery and placed 100

on the market at a very low price; also, as each pocket is formed independently of its own sheet and as the pockets are all connected by a single sheet perforated between the pockets one or more pockets can be easily and quickly detached along the perforated single thickness of paper connecting the pockets without the least danger of tearing through a pocket or in any other way injuring the pocket detached or those remaining in the series, particularly in view of the fact that the back of each pocket is made up of several thicknesses of paper and the weakest points in the series are those between the pockets.

15 A series of paper pockets made as herein set forth can easily receive cigars of various sizes and shapes without locking or contracting any other pocket in the series because of the fact that each pocket is formed separately 20 with a stiffened back of double thickness, allowing the front wall of each pocket to bulge or move outwardly to the full capacity of the pocket entirely independently of the remaining pockets; also, each pocket when detached 25 is in perfect condition and capable of receiving and protecting a cigar, which can be easily inserted therein, as the folds ^{b2} permit easy and ready opening of the mouth of the pocket, and as the ends of the sheet forming the pocket 30 are pasted to the section of the backing-sheet, making several thicknesses at the back of the pocket, so that a single detached pocket is stiffened so as to be of utility for the purpose stated.

35 Having thus fully described my invention, what I claim as new, and desire to secure by Letters Patent of the United States, is—

1. A series of paper cigar-pockets composed of a single paper backing-sheet formed with 40 the transverse parallel lines of perforations, and the series of independently-formed de-

tachable pockets arranged parallel with each other on one side of the sheet and between the lines of perforations, each pocket formed of its own sheet of paper folded to form the 45 closed front, collapsible sides, and the rear wall where the two ends of the sheet are pasted to the backing-sheet between two lines of perforations therein so that each pocket has its rear wall formed of several thicknesses and 50 the several pockets are connected only by the perforated portions of the single backing-sheet, substantially as described.

2. As an article of manufacture, a series of pockets, each constructed of an independent 55 piece of paper, and pasted side by side on one surface only of a single sheet of paper constituting the only backing for said series of pockets, said sheet being perforated between each pair of said pockets, substantially as de- 60 scribed.

3. As an article of manufacture, a sheet or series of cigar-pockets made up of a paper backing-sheet on one side only of the pockets formed with series of transverse, parallel, 65 equally-spaced lines of perforations, and individually separate pockets arranged on one side of the sheet between the lines of perforations, each pocket formed of a single sheet of paper folded to form the front and sides 70 with its two ends brought together, or approximately so, and pasted on the backing, the lower end of the backing-sheet pasted over and closing the lower ends of the pockets, substantially as described.

75 In testimony whereof I affix my signature in the presence of two witnesses.

ORVILLE L. PARMENTER.
